UNITED STATES PATENT OFFICE.

WILLIAM J. LANE, OF POUGHKEEPSIE, NEW YORK.

DESIGN FOR A STORM-CAP.

SPECIFICATION forming part of Design No. 29,796, dated December 13, 1898.

Application filed November 4, 1898. Serial No. 695,509. Term of patent 14 years.

To all whom it may concern:

Be it known that I, WILLIAM J. LANE, a citizen of the United States, residing at Poughkeepsie, in the county of Dutchess and State of New York, have invented and produced a new and original Design for a Storm-Cap; and I do declare the following to be a full, clear, and exact description of the same, reference being had to the accompanying drawings, forming a part thereof.

My design consists in the novel article of manufacture shown and described.

Figure 1 is a perspective view of my design for a storm-cap. Fig. 2 is an end view of my

design for a storm-cap, showing its general outline.

The design consists, essentially, of the vertical portions A and B as viewed in connection with the inclined portion C.

I claim—

The design for a storm-cap substantially as shown and described.

In testimony whereof I affix my signature in the presence of two witnesses.

WILLIAM J. LANE.
